CLAIM

The ornamental design for a wireless mouse, as shown and described.

DESCRIPTION

FIG. 1 is a perspective view of a wireless mouse comprising the Applicant's design;

FIG. 2 is a side view of the mouse of FIG. 1;

FIG. 3 is a top-down view of the mouse of FIG. 1;

FIG. 4 is a front-end view of the mouse of FIG. 1;

FIG. 5 is a bottom-up view of the mouse of FIG. 1; and,

FIG. 6 is a rear-end view of the mouse of FIG. 1.

The broken lines shown in the drawings represent portions of the wireless mouse that form no part of the claimed design.
